DESIGN FOR A BEVERAGE COOLER CABINET

Ralph E. Kruck, Springfield, Mass., assignor to
Westinghouse Electric & Manufacturing Com-
pany, a corporation of Pennsylvania

Application August 6, 1936, Serial No. 64,272

Term of patent 7 years

To all whom it may concern:

Be it known that I, Ralph E. Kruck, a citizen of the United States, residing at Springfield, in the county of Hampden and State of Massachusetts, have invented a new, original, and ornamental Design for a Beverage Cooler Cabinet, of which the following is a specification, reference being had to the accompanying drawing forming part thereof:

Fig. 1 is a side elevational view of the beverage cooler cabinet showing my new design;

Fig. 2 is an end elevational view of the beverage cooler cabinet; and

Fig. 3 is a perspective view of the beverage cooler cabinet.

I claim:

The ornamental design for a beverage cooler cabinet substantially as shown.

RALPH E. KRUCK.
